(57) **CLAIM**

The ornamental design for a foldable nail lamp, as shown and described.

DESCRIPTION

FIG. 1 is a front, right and top perspective view of a foldable nail lamp showing our new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front, right and top perspective view of the foldable nail lamp in another configuration; and,

FIG. 10 is a rear, left and bottom perspective view thereof. The broken lines in the drawings illustrate portions of the foldable nail lamp that form no part of the claimed design.
